(57) **CLAIM**

The ornamental design for an operator seat for industrial vehicle, as shown and described.

DESCRIPTION

FIG. 1 is a perspective view for an operator seat of an industrial vehicle;

FIG. 2 is a front elevation view thereof;

FIG. 3 is a left side elevation view thereof, the opposite being a mirror image of that shown; and,

FIG. 4 is a top plan view thereof.

The bottom and back of this design form no part of the claimed design and so are not included herein.

1 Claim, 4 Drawing Sheets

FIG.1

FIG.2

FIG.3
